UNITED STATES PATENT OFFICE.

EUGENE E. YOUNG, OF SYRACUSE, NEW YORK.

CARBON-ELIMINATOR AND LUBRICATOR FOR GAS-ENGINES.

1,305,859.

Specification of Letters Patent.

Patented June 3, 1919.

Application filed November 23, 1918. Serial No. 263,893.

To all whom it may concern:

Be it known that I, EUGENE E. YOUNG, a citizen of the United States, residing at Syracuse, in the county of Onondaga and

5 State of New York, have invented certain new and useful Improvements in Carbon-Eliminators and Lubricators for Gas-Engines, of which the following is a specification.

10 This invention relates to means for eliminating carbon in gas-engines, and has for its object to provide a novel, simple and effective device of the class, which collects the hot vapor or steam generated by the radiator 15 of an automobile and conducts and discharges the same under certain regulating means into the intake manifold of the engine, where it is mixed with the explosive gas supplied by the carburetor for weakening the mixture, as well as for supplying the requisite moisture within the explosive chambers for preventing the accumulation of carbon therein. A further object of the invention is to provide novel and simple means 25 for lubricating the engine cylinders. And a further object is to utilize certain parts of the main device for effecting the priming of the engine when the latter is started.

I attain these objects by the means set 30 forth in the detailed description which follows, and as illustrated by the accompanying drawing, in which—

Figure 1 is a perspective view of the front portion of an automobile, with parts broken 35 away; showing the construction, arrangement and operation of the improvement.

Fig. 2 is an enlarged sectional view of the top of the auto-radiator; showing certain parts of the invention applied thereto.

40 Fig. 3 is an enlarged sectional view of the cock which controls the flow of the steam from the radiator to the engine.

Fig. 4 is an enlarged view, partially in elevation and partially in section, showing 45 the construction of a convenient form of needle-valve for controlling the flow of the priming mixture.

Fig. 5 is an enlarged sectional view of the butterfly valve which is automatically operated by the throttle operating mechanism.

In the drawing, 2 represents generally the gas-engine of an automobile, 3 is the radiator, on the top of which is disposed the usual filling-neck 4, which is closed by a cap 5. 55 6 is a conventional representation of a car-

buretor, with which is associated the usual throttle, the latter being operated by a crank 7 and a rod 8, and 9 is the dash, which supports certain parts of the new mechanism.

In carrying out the objects and working 60 of the invention, I make use of the hot vapor or steam, which is practically constantly present in the top portion of the radiator 3, and for this purpose, I insert one end of a pipe 10 into the top of the radiator, and 65 mount upon the said end a nozzle 11, whose flaring mouth is preferably shielded by a gauze cap 12. The pipe 10 is preferably bent upwardly, so as to position the nozzle 11 within the neck 4 above and clear of the 70 water and other liquid contained by the radiator. A check-valve 13 inclosed in a tube 14 is inserted through a perforation in the top of the cap 5, for providing varying 75 quantities of oxygen to be mixed with the explosive gas under certain conditions, but prevents the water and steam from escaping through said vent. The tube 10 then extends rearwardly, preferably beneath the hood 15 and passes through the dash 9, where it is 80 attached to a cock 16, which permits or prevents the passage of the steam and air from the radiator to the engine. The plug 16' of the cock may be operated manually, by the 85 driver of the car, for gaging the volume of the steam to be supplied to the engine according to the state of the weather and other conditions, by means of a rod 17, to which is rigidly attached a pointer 18, and which is arranged to play over an indicator dial 90 19, the latter having upon its face certain letters and figures which indicate several positions to which the plug 16' may be rotated and set. A second section of the tube, as 10' connects the cock 16 with a T 20, and 95 a third section, as 10'', extends from the T 20 through the dash 9, and thence forwardly at an incline, to a point directly over the carburetor 6, where it connects with the body of a butterfly valve 22, the said valve being 100 supported by the intake manifold and operated by a crank 23.

The gasoline for operating the engine is supplied by a tank 24, which in the present case is mounted on the front side of the dash 105 9, beneath the hood, the gasoline being conducted by gravity to the carburetor 6 by a pipe 26. To provide novel and simple means for priming the engine for starting the same, by utilizing certain parts of my steam in- 110

jecting mechanism, I tap the supply-pipe 26, as at 27, by a pipe 28, which connects with the T 20, and in this pipe I dispose a needle-valve, designated generally by the numeral 29, and which controls the flow of the gasoline from the pipe 26 to the pipe 10". The needle-valve 29 is operated by a rotatable rod 30, which is supported by the dash, and the said valve may be operated at will by

10 the driver of the car, for feeding suitable charges of gasoline directly into the intake manifold 31, for priming the engine, instead of waiting for the slower and smaller feeding of the gas from the carbureter.

15 The butterfly valve 22 is operated by a rod 32, which is positioned substantially parallel to the throttle-operating rod 8, and these two rods are pivotally connected to the opposite ends of a rocking lever 33, which

20 is supported by and rocks with a shaft 34 located beneath the floor 35. The lever 33 is rocked by means of a pedal-pin 36, which comprises a part of the well-known foot accelerator. The full lines in Fig. 1 show

25 the positions of the rods 8 and 32 when the throttle 7 is open and the butterfly valve 22 is closed (see Fig. 5). The dotted lines in Fig. 1 indicate that the throttle is closed and the butterfly valve is open.

30 To provide in a novel and simple way for the lubrication of the engine cylinders, I pour a suitable quantity of lubricating and kerosene oil into the top of the radiator, where it floats upon the water, as shown at 37 in Fig. 1. The high temperature of the water in the radiator tends to volatilize the oils, and their vapors are drawn off and conducted to the cylinders together with the steam, thus providing an extremely simple, 35 practical and economic method of lubrication, which does away with the usual more or less complicated lubricating mechanisms.

The operation of my improvement is as follows: To start the engine, the throttle is 40 usually first operated to the open position, which automatically closes the butterfly valve 22, as shown in Fig. 5. The driver then opens the needle-valve 29 for a moment to allow a charge of the gasoline contained 45 in the tank 24 to gravitate through the pipe 10" to the manifold 31. The valve 22 does not entirely close the passage through its casing, so that the gasoline filters through said valve and the first suction of the pistons 50 draws the gas directly into the cylinders and starts the engine. As soon as the engine warms up, the cock 16 should be opened to the desired extent, which allows the hot vapor, or air at atmospheric temperature, 55 and the lubricant to be drawn toward the cylinders. The throttle is then closed or partially closed, as usual, which operation correspondingly opens the valve 22 for the admission of the steam and lubricant into 60 the cylinders. If the weather is warm, the

cock 16 is left open to whatever extent the conditions of the weather and the speed of the car require. In cold weather, the cock 16 should be left closed until the engine becomes hot enough to generate the steam or 70 hot vapor in the radiator. When the car is being driven at high speed and rich gas is required, the cock 16 should be closed sufficiently to allow barely enough of the steam or hot vapor to pass from the radiator to the 75 engine to prevent the accumulation of carbon in the cylinders, on the spark-plugs, and valves, and to lubricate the upper ends of the pistons. But when traveling at low speed, when less power is required, it is desirable 80 to weaken the gas supplied by the carbureter, and this is accomplished by the driver by opening the cock 16 to a greater extent, for allowing the requisite amount of the diluting fluid or vapor to be drawn into 85 the engine. In this way the carbureter needs no change of adjustment, and the explosive mixture supplied by it may be enriched or weakened at will, by the simple manipulation of the rod 17, which supports 90 the indicator 18, and which is located within easy reach of the driver of the car.

Having thus described my invention, what I claim as new and desire to secure by Letters Patent is—

95 1. A tube adapted to draw steam from the radiator of a gas-engine, a valve adapted to control the admission of the steam into the intake manifold of the engine, a cock connected to said tube between the radiator and said valve adapted to gage the flow of the steam through said tube independently of said valve, means for indicating the extent said cock is opened, and a rocking lever adapted to open the throttle of the engine 100 and close said valve simultaneously.

2. The combination with the intake manifold, the throttle, and the radiator of a gas-engine, said radiator having a fresh air inlet valve, of a tube for conducting hot vapor 110 mixed with fresh air from said radiator to said manifold, a cock and an indicator associated therewith for gaging the volume of the vapor passing through said tube, a butterfly valve supported by said tube between 115 the cock and the manifold, and a rocking lever adapted to open said valve while closing the throttle, and vice versa.

3. In a device of the class described, a butterfly valve, a tube connecting said valve 120 with the radiator of a gas-engine, a cock interposed between said valve and the radiator and controlling the flow of aqueous vapor from the radiator to said valve, a throttle operating mechanism including a rocking 125 lever and a pair of rods connecting said lever respectively with the throttle and with said valve, said rods adapted to move in opposite directions by the rocking of said lever for closing said valve while the engine is op- 130

erated at high speed, and for opening said valve when the speed of the engine is reduced.

4. The combination with a radiator and a
5 gas-engine having a throttle and an intake
manifold, of a pipe tapping the radiator for
conducting hot vapor to said manifold, a
10 valve supported by the manifold and con-
nected to said pipe, a throttle operating
mechanism including a rocking lever and a
rod, a second rod operatively connecting
15 said lever with said valve, said rods adapted
to be moved in opposite directions by the
rocking of said lever for simultaneously
opening the throttle and for closing said
valve and vice versa, and a cock for prede-
termining the flow of the vapor to said
valve.

5. The combination with the radiator and
the throttle operating mechanism of an in- 20
ternal combustion engine, of means for in-
jecting hot vapor into the engine ahead of
the throttle comprising a tube having one
end inserted in the top of the radiator, a
25 valve mounted above the throttle and con-
nected to the opposite end of said tube,
means for operatively connecting said valve
with said mechanism, whereby said valve is
automatically opened when the throttle is
30 closed and vice versa, and manually operated
means interposed between said valve and the
radiator for independently gaging the vol-
ume of the vapor passing through said tube.

In testimony whereof I affix my signature.

EUGENE E. YOUNG.
